UNITED STATES PATENT OFFICE

151,083

DESIGN FOR A COAT

John F. Strassner, New York, N. Y.

Application January 13, 1948, Serial No. 143,712

Term of patent 3½ years

(Cl. D3—4)

To all whom it may concern:

Be it known that I, John F. Strassner, a citizen of the United States, residing in New York city, in the county of New York and State of New York, have invented a new, original, and ornamental Design for a Coat, of which the following is a specification, reference being had to the accompanying drawing, forming part thereof.

Fig. 1 is a front view of a coat, showing my new design, and

Fig. 2 is the rear view thereof.

I claim:

The ornamental design for a coat, substantially as shown.

JOHN F. STRASSNER.
